UNITED STATES PATENT OFFICE.

WILLIAM L. DEMING, OF SALEM, OHIO.

READING-STAND.

1,257,586.

Specification of Letters Patent.

Patented Feb. 26, 1918.

Application filed June 24, 1915. Serial No. 36,041.

To all whom it may concern:

Be it known that I, WILLIAM L. DEMING, a citizen of the United States, residing at Salem, in the county of Columbiana and State of Ohio, have invented a certain new and useful Improvement in Reading-Stands, of which the following is a full, clear, and exact description, reference being had to the accompanying drawings.

10. The object of this invention is to provide a simple convenient reading stand adapted for the holding of reading matter, such as music, periodicals, manuscripts and the like. Another object is to provide a table-like support in connection with the stand adapted to receive appurtenances requisite for lecturing, reading or the directing of music. Another object is to so arrange the reading support that it is vertically and laterally adjustable to various positions with relation to its base so that it may extend over a chair or the side of a bed, or be brought to a suitable position for reading while standing. Another object is to provide extensible members 15 on the support for the edges of large sheets of reading matter, which members may be rigid when extended and collapsible to a position directly underneath the support. Still other objects are to provide an adjustable lamp fixture carried by the stand and to provide one rack underneath the table-like support, adapted to hold books and being so positioned as to balance the reading support, and another rack for newspapers and the like.

20. My invention is illustrated in the accompanying drawings in connection with which it is hereinafter more fully described, and the essential characteristics are set forth in the claims.

In the drawings, Figure 1 is a perspective view of my reading stand; Fig. 2 is a side elevation of the upper portion of the stand and the table with which it is associated, the lower portion being sectioned; Fig. 3 is a detail of the offset arm carrying the stand, showing the swivel feature; Fig. 4 is a detail of the upright clamping member connected with the arm shown in Fig. 3; Fig. 5 is an enlarged sectional detail through the clamping member and plug 27, showing the means for holding the same in position; Fig. 6 is an enlarged transverse section through the pedestal, taken on the line 6—6 of Fig. 2; Fig. 7 is a horizontal sectional detail through the ferrule, taken on the line 7—7 of Fig. 2;

Fig. 8 is a bottom plan of a portion of the reading support, showing one of the extensible members; Fig. 9 is an edge view of the same; Fig. 10 is a side elevation of the book rack secured to the lower end of the table, and Fig. 11 is a side elevation of a bracket for newspapers and the like.

Referring to the drawings by reference numerals, 10 indicates a table top which may be of any suitable form, preferably round, shown as carried on a standard 11 rising from a pedestal indicated at 12. The table top 10 is secured to the standard by a ferrule 14 tightly fitting over the upper end thereof and shown as having a solid portion above the standard and provided with integral outwardly extending ears 15. These ears lie in a horizontal plane and are provided with screw-holes 16 for screws securing the table top thereto. On the under side of the top may be provided cleats indicated at 17, to add strength and rigidity.

Rising from the center of the table top and extending downwardly into an axial passage in the standard 11, is a revoluble rod 18, extending axially through the member 14. This ferrule is provided with a transverse thumb screw 20 bearing against a soft metal plug 21, which in turn engages the rod 18, allowing the same to be vertically and revolvably adjusted and providing for making the same rigid in any desired position. A transverse bore 22 in axial alignment with the screw 20 and of sufficient size to admit the plug 21 allows the same to be put in position, after which the bore is closed by a suitable plug 23.

Rigidly mounted on the upper end of the rod 18 is a laterally extending arm 24, being provided with a down-turned elbow 25, engaging the member 18 and provided with an upturned end 26, which carries an upwardly projecting lug 27 having an annular groove 28. This lug is adapted to fit a bore in the lower end of a clamping member 30, shown as provided with a staple 31 having its legs engaging the groove 28 to revolvably secure the clamping member to the arm 24. The clamping member is bifurcated at its upper end to engage a downwardly extending web 32 having a slot 33 through which passes a thumb screw 34, which is adapted to draw the bifurcated portion of the clamping member into a tight engagement with the web 32. The clamping member is shown as provided with a slot 36, extending nearly

to the lower end of the clamping member whereby it may be clamped onto the upper cylindrical portion of the plug 27 when the screw 34 is tightened onto the web member 32.

The web member 32 has laterally extending ears 35 by which it is secured to the middle portion of the under side of a reading support 36, shown as comprising a flat rectangular board-like member having at its lower edge an upwardly projecting flange 37 adapted to engage the lower edge of music, periodicals or other reading matter.

Laterally extensible members are provided on this rack to support the outer sides and corners of large sheets of music or large periodicals, and I prefer to construct such members as follows. On the under side of the board member 36, I have mounted two substantially rectangular members 40 preferably stamped from sheet metal and each comprising a rectangular frame portion having a pair of substantially diagonal cords 42 spaced apart to leave a slot 43. These slots are adapted to engage screws 44, which pass through the slots and into the board 36 and are provided with suitable washers indicated at 45 for supporting these extensible members while allowing them to be slid longitudinally of the slot 43. Around the lower screws 44 are spring washers 47 adapted to hold the inner corners outwardly from the board, slightly raising the upper corners, as shown in Fig. 9, bringing them substantially to the upper plane of the board 36.

It is also desirable to provide an adjustable electric lamp associated with the device. Accordingly I mount a lamp 50, provided with a reflector 52, on an upwardly extending arm 53, which is carried by one of the jaws 54 of a spring clamp having a spring 56 adapted to press the jaws of the clamp together on the board 36 at any portion of its edge. The jaw engaging the upper side of the board is preferably provided with an elastic pad 57 to prevent marring the same.

Suitable wire cord 60 may lead through the tubular arm 53, to the lamp and downwardly to an opening 61 in the elbow 26 of the swinging arm 24, through this arm and downwardly through the tube 18 and outwardly through the lower portion of the axial bore in the pedestal, where it may be provided with a suitable plug fitting 63, adapted for attachment to any lamp socket. It is desirable not to allow the cord to wind around the upright clamping member 30 or to become otherwise tangled around the board 36, accordingly I may prevent the complete revolution of the swiveled rod support by a downwardly extending lug 65, rigid with the clamping member 30 and adapted to engage a short web 66 formed on

the inside of the elbow 26 of the arm 24. This lug engaging the web prevents a complete revolution in either direction and necessarily prevents the rod support rotating a number of times and thereby winding and tangling the cord for the lamp.

It is preferable to limit the motion of the laterally extending arm 24 to an arc equivalent to a quarter of a circle or thereabout. This I prefer to accomplish by providing a laterally extending lug 70 on the lower end of the rod 18, and the axial passage in the upright 11, preferably comprises two semicircular grooves; one fitting the rod 18 and the other, indicated at 72, being considerably larger and adapted to admit the lug 70. The upright being made in two halves brought together with these grooves registering provides shoulders at 73, either side of the smaller groove, against which the sides of the lugs 70 may engage to limit the turning motion of the rod 18; which, as heretofore stated, is rigidly attached to the laterally extending arm 24. The rod 18 may be of sufficient length to permit this lug to be attached at the lower end beneath the pedestal and then drawn upwardly into the passage, or I may provide a removable plate 75 closing the upper end of this bore and normally acting as a guide for the rod 18 and which will permit this lug to be inserted from the upper end.

Accordingly it will be seen that the stand is carried above the table member 10 and normally at one side of the pedestal, and its weight may be counterbalanced by books arranged on a book rack at the opposite side of the pedestal and beneath the table. Such a book rack is shown as comprising a flat metal strip 78 having a flat U-shaped portion 79 from which extend upwardly two supporting legs 80. These legs lie substantially in the same plane and are curved inwardly to a position where they may rest against a flat boss 81 formed on the ferrule member 14 and against which they may be clamped by a washer 82 and screw 83. The legs extend upwardly from the washer and are curved outwardly and twisted so that at their upper ends they may have outwardly extending ears 85 lying in a substantially horizontal plane and engaging the upper side of tongues or flanges 86 on the transverse members 17. The bottom of the rack comprises a flat board member 87 carried on the horizontal loop 79 of the strip 80, and the ends of the rack comprise two U-shaped members 88 having their ends turned under the board and secured thereto by suitable screws. On the opposite side of the upright 11 from the book rack I prefer to provide a rack for periodicals, newspapers, etc., which comprises a single strip of wire bent to provide two depending legs 90, secured by eyes secured to the under side of

the table top by a screw 91. The legs 90 are bent forwardly and then upwardly at their lower ends, where are formed two inverted U-shaped members 92 serving as a 5 vertical support at the front side of the rack. From each of the adjacent legs of these inverted U-shaped members the wire leads backwardly and upwardly at 94, where it is curved around the pedestal and looped 10 over the screw 83. Here the wire is secured between the washer 82 and the washer 95, bracing these curved wires and stiffening the newspaper support. Thus the legs 90 and 94 form one side of the support while 15 the U members 92 form the other side, and the connecting portions at the lower ends of each of these form the bottom supports for the rack.

It will be seen from the foregoing description that I have provided a reading stand comprising a table member on which any suitable articles may be laid; a rack for holding the reading matter, and an adjustable support for such rack which is carried 20 on an offset arm adapted to allow the rack to be swung laterally into a reading position over the side of a chair or bed. It will also be noted that the long slot 33 in the web 32 allows the rack to be moved forward and back with relation to the center 25 of the table, and the clamping member 30 permits the support to be adjusted to various angles with relation to the table. The extensible members on the support are compact, simple and not apt to get out of order, as well as being adapted to be moved to a 30 position entirely within the outline of the supporting member itself, and it will be noted that the support may be collapsed to 35 a position close to the table top and the lamp removed, permitting the table to be stored or shipped in small compass.

Having thus described my invention, what I claim is:

45 1. The combination, with a base, of a substantially flat support for reading matter, means rising from the base for carrying the support, a pair of extensible members secured near the corners of the support and 50 having diagonal slots, means occupying said slots and loosely engaging the same allowing said members to be slid longitudinally of the slots from a position within the outline of said support to a position projecting 55 outwardly beyond the top and ends of the same.

2. The combination with a support comprising a substantially flat member, a depending rib on the under side of said member having a longitudinal slot, a stand, a movable arm carried by the stand, a clamping member swiveled to said arm on a vertical pivot, a bolt extending through the

slot of the rib and carried by the clamping member, and means for clamping the clamping member to the arm when the bolt is tightened to clamp the rib to the clamping member. 65

3. The combination, of a reading support comprising a substantially flat member, a 70 depending rib on the under side of said support and having a longitudinal slot, a clamping member having a screw extending through said slot, an offset arm having an upwardly extending lug, said clamping 75 member being hollow at its lower end and rotatably engaging said lug and being split vertically whereby said screw may act to tighten the clamping member onto both the rib and lug. 80

4. The combination, with a book support, of a device for carrying the same including means permitting it to be moved transversely of the carrying means and brought to various slanting positions, said carrying 85 means including an upright swivel member permitting the support to be rotated in a horizontal plane, and a clamping device connected with the swivel member and adapted when tightened to prevent any of 90 said movements of the support.

5. In a reading stand, the combination of a book support, a depending rib on the under side of said support, a clamping member engaging the rib, an upward projection 95 about which said clamping member may rotate in a horizontal plane, and a device for causing the clamping member at the same time to tightly grip said rib and said projection. 100

6. In a reading stand, the combination of a book support, a depending rib on the under side of said support having a longitudinal slot, a clamping member engaging the side of said rib and having a screw extending through said slot, an upward projection rotatably engaged by said clamping member, and means whereby the clamping member tightly grips said projection when the screw is tightened to clamp the rib. 110

7. In a reading support, the combination of a substantially flat member, a depending rib on the under side of said member having a longitudinal slot, a bifurcated clamping member embracing the sides of 115 said rib and having a screw extending through said slot, an upward projection rotatably embraced by said clamping member, means for preventing the removal of the clamping member from the projection, the 120 clamping member being adapted to tightly grip said projection when the screw is tightened to clamp the rib.

In testimony whereof, I hereunto affix my signature.

WILLIAM L. DEMING.
